UNITED STATES PATENT OFFICE.

DAVID R. KOLODNY, OF BROOKLYN, NEW YORK.

WATER-TIGHT CONTAINER FOR USE OF BATHERS.

1,331,508.

Specification of Letters Patent. Patented Feb. 24, 1920.

Application filed September 16, 1918. Serial No. 254,340.

To all whom it may concern:

Be it known that I, DAVID R. KOLODNY, a citizen of Russia, and a resident of Brooklyn, in the county of Kings and State of New York, have invented a certain new and useful Water-Tight Container for Use of Bathers, of which the following is a specification, the same being a full, clear, and exact description of the invention, such as will enable others skilled in the art to which it appertains to make and use the same.

This invention relates to cases or receptacles for articles of any kind, and particularly to a watertight container constructed and arranged to be attached to or sustained by a band or belt worn around or hooked to the waist and constructed of a material adapted to be uninjured by the action of water; or, if preferred, to be supported directly by a bathing suit or other garment.

Generally stated, the object of my invention is to provide a novel and efficient device of the foregoing general character, together with certain characteristic details and features of construction, tending to produce an article that shall be simple in construction, inexpensive to manufacture, and convenient and durable in practical use. To these and other useful ends my invention consists in the matters hereinafter more fully set forth.

It has been deemed desirable by me to provide a watertight case or receptacle for the use of bathers at the seashore or other bodies of water, which container shall be adapted to preserve in a dry condition cigarettes, etc.—or for ladies' use articles of jewelry, powder puffs, etc.—access to which articles may be readily had at any desired time without danger of any injury to the same occurring by the splashing of any water thereon.

In the drawings which illustrate embodiments of my invention and which accompany and form a part of this specification, Figure 1 represents a top view of an article constructed according to my invention without the cover; Fig. 2 is a view of the cover detached from the box; Fig. 3 is a view of the open front of the case; Fig. 4 is a partial side view of the open receptacle the cover hanging down; Figs. 5 and 6 are details of a locking device for the cover.

Like numerals of reference indicate like parts in all the views.

Referring particularly to the drawings, 3 denotes the body portion, of a receptacle or

container constructed according to my invention, which container may be of any desired size or pattern and constructed of any suitable material that will not become injured by the action of water thereon, as for example sheet aluminum. The said body portion is imperforate and is provided with a suitable closure as an imperforate cover 4 and intermediate waterproof material 5, as a packing or gasket, the parts being so arranged that by the superposition of the cover 4 on the body portion 3 a sealed closure is formed impervious to the action of water thereon.

In the example of the invention shown in Fig. 1 an inwardly projecting beveled flange or turned in flexible edge 10 will be seen to extend around the front of the container 3, and an oppositely disposed projecting beveled flange or turned out flexible edge 10 extends outwardly from the cover 4. Each of the said flanges has a groove 9 in which the gasket 5 is placed. The flanged edges of the container and the gasket will prevent any drops of water that may lie upon the cover from entering the receptacle when the latter is opened. The cover may be hinged to the container as at 18.

I also provide means for locking the cover to the container as by means of a catch 19 projecting from the cover which engages, when the cover is closed, the spring lever 21 of the lock 20, whereby the parts are held together. In order to release the cover it is only necessary to press the button 22 which disengages the spring lever 21 from the catch 19.

The container may be supported in any suitable manner as by being attached to a belt or to any other article of apparel not deleteriously affected by water by suitable means, which means may comprise sewing, pinning or riveting operations, etc., by which combination of parts the support and container and articles inclosed therein will not be damaged in use by the repeated and continuous insertion of the whole in the water.

The details of construction of my container may be varied at will so long as the general characteristic features thereof are retained. One convenient disposition of the packing 5 consists in inserting a gasket, or other flexible waterproof material, in a groove extending around the top edge of the body of the container, into which a depending flange of the cover may enter when the

closure is made, the top and bottom of the container as an entirety then being in a parallel relation. The cover may have an overlapping edge 15 for the purpose of shedding water and to prevent the same from dropping into the interior of the container when opened.

It will be noted that the grooves respectively formed in the inclined flanges lie at an angle to the same and are spaced from and lie at right angles to the top and bottom faces of the container and closure—the gasket mounted in one of said grooves being positioned parallel with the sides of the container. On account of the flexibility of the said flanges, the latter and intermediate gasket will always form a tight joint at the meeting faces of the parts even when the gasket becomes worn from use.

I wish it to be understood that I do not desire to be limited to the particular use or the exact details of construction shown and described, for obvious modifications will occur to persons skilled in the art.

What I claim as my invention is:

In a device of the class described, a container made of flexible material and formed with an angular interiorly extending and de-

pressed tapered flange and the upper edge of the same forming an inclined ledge around the entire top of the container, and a closure therefor made of similar material and formed with an angular exteriorly and inwardly directed tapered flange around the edge thereof forming a projection around the upper part of the closure to register and contact with the first named flange to form a tight joint at the meeting faces thereof, and also grooves respectively formed in the said inclined flanges, and a gasket mounted in one of said grooves, whereby on account of the flexibility of the said flanges, the latter and intermediate gasket will always form a watertight joint at the said meeting faces, even when the gasket becomes worn down from use.

In testimony of the foregoing specification I do hereby sign the same in the borough of Brooklyn, of the city of New York, in the county of Kings and State of New York, this 9th day of September, 1918.

DAVID R. KOLODNY.
